UNITED STATES PATENT OFFICE.

EDWARD J. ABBOTT, OF MISSION CITY, BRITISH COLUMBIA, CANADA.

ENVELOP SEALING AND STAMPING MACHINE.

959,283.

specification of Letters Patent. Patented May 24, 1910.

Application filed May 10, 1909. Serial No. 495,018.

To all whom it may concern:

Be it known that I, EDWARD J. ABBOTT, citizen of the Dominion of Canada, residing at Mission City, in the Province of British Columbia, Canada, have invented a new and useful Improvement in Envelop Sealing and Stamping Machines, of which the following is a specification.

This invention relates to a machine for moistening the flaps of envelopes and sealing them, and for simultaneously affixing postage stamps thereto.

It is particularly described in the following specification, reference being made to the drawings by which it is accompanied, in which:

Figure 1 is a longitudinal section on the line A A in Fig. 6 showing the means by which the envelopes are withdrawn from the receptacle in which they are placed and their flaps moistened and closed, Fig. 2, a side elevation of the machine, Fig. 3, a longitudinal section on the line B B in Fig. 6, Fig. 4, a cross section on the line C C in Fig. 6, Fig. 5, an end elevation of and part section through the envelop holding receptacle showing the means whereby the envelop moistening slide is wetted, and Fig. 6 a general plan of the machine. Fig. 7, is an enlarged detail view hereinafter referred to. Fig. 8, is an enlarged detail view of a part of my invention.

In these drawings 2 represents the frame of the machine to which the several parts of its mechanism are attached and connected, which frame is designed to rest upon a table or desk.

Pivottally mounted on screws 3 through the side frames of the machine is an envelop holding receptacle 4, adapted generally in length and breadth to the size of envelop required, and provided with light centering guides 5 flexibly depending from the upper edges of its sides and adjustable at the lower end by means of screws 6 as shown in Fig. 5.

The envelop holding receptacle 4 is open at the bottom, save for a ledge 7 projecting inward across the back, and the pivotal axis 8 is toward the back of the receptacle so that its front edge rests upon a roller 10 freely rotatable in bearings 11 which are vertically movable downward in the side frames 2 against the resistance of springs 12. A portion of the weight of the receptacle thus

rests upon the roller 10 and this pressure 55 may be supplemented by a spring 8 secured to the frame 2 and bearing against the upper part of the back of the receptacle.

Slidable in guides 13 in the side frames 2, at the approximate level of the bottom of 60 the receptacle 4, is a plate 14 beveled toward its front edge and having on its under side a pad 15 of absorbent material designed to moisten the gummed flap of the envelop, which absorbent pad is wetted in a manner 65 to be described later. The plate 14 is horizontally reciprocated in its guides by levers 16, secured on each side of the machine on a shaft 17 rockable in bearings 18 in the side frames 2, and these levers 16 are oscillated 70 by a rod 19 connected to one of the levers from a crank pin 20 secured on one end of the shaft of a roller 21 from which shaft all the movements of the machine are derived and which is rotated by means of a han- 75 dle 22.

Pivottally mounted at 23 with its front end under the slide plate 14 is a water holding vessel 24, the front end of which is designed to hold a sponge 24^x or the like. The front 80 end of this water holding vessel rests upon a lever 25, pivotally mounted at 26 in the side frame 2, the outer end 27 of which lever projects in the path of the end 28 of the connecting rod 19 when that rod is at the 85 back end of its stroke, so that when the connecting rod 19 is sliding back the plate 14 the end 28 of the rod presses down the end 27 of the lever 25 and lifts the sponge holding front end of the vessel 24 upward and 90 into contact with the absorbent pad 15 of the slide plate 14.

Between the roller 10 and the roller 21, and having its upper side in approximate alinement therewith, is a roller 30 rotatable 95 in bearings 31 downwardly movable in guides in the side frame against the resistance of springs in a similar manner to the roller 10. Around the rollers 21 and 30 is stretched a band of flexible fabric 32 which 100 fabric is supported between the rollers by a bearing plate 33 which plate may be carried on the shaft of the roller 30 so as to be movable downward with it. Rotatable in bearings in the side frame immediately 105 over the rollers 21 and 30 are rollers 35 and 36, 35 being driven from the roller 21 by gear wheels 37 and 38, and over these

rollers 35 and 36 are stretched fabric bands 39 to hold the envelopes down with a yielding pressure between the rollers.

The mechanism so far described is that 5 by which the envelopes are withdrawn from the receptacle and their gummed flaps moistened and closed upon the body of the envelop.

In operation the envelopes are placed horizontally in the receptacle with their gummed flaps downward and the free edges of them directed backward, with which arrangement, the back edge of the lower envelop rests upon the ledge 7 and its front edge 10 upon the roller 10, the gummed flap directed backward beyond the lower edge of the receptacle and in the path of the plate 14, the absorbent pad 15 of which has been moistened during the backward stroke by 15 contact with the sponge in the water vessel 24 which sponge was lifted into contact with it in the manner previously described. On rotation by the handle 22 the plate 14 is moved forward and engages the flap of the 20 envelop from under the front edge of the receptacle 4, which is lifted during the movement to permit it to pass, and during this movement the moistened pad 15 wets the gum on the flap. The plate 14 delivers 25 the front edge of the envelop between the rollers 30 and 35 which engage it and carry it forward, while the plate 14 recedes to receive the next one and in that backward movement effectually completes the wetting 30 of the gummed flap by rubbing its moistened absorbent pad over it. As the envelop passes through the rolls 30, 35 and 21, 36 it is tightly pressed by means of the springs 35 12* which control the movement of the 40 rollers and its gummed and moistened flap is effectually sealed upon the body of the envelop which is delivered from the front end of the machine which may if found necessary be provided with a chute 40 for such 45 delivery.

Situated on one side of the machine corresponding to the side of the envelop to which it is desired to affix the postage stamp is the mechanism by which the corner of the 50 envelop is moistened and the postage stamp applied.

The envelop moistening device shown in Figs. 2 3 and 7 consists of a small water containing vessel 41 connected by a capillary tube to a sponge or other similar absorbent material secured in a frame beneath. This 55 water vessel 41 and its absorbent pad is supported on a stem 42 vertically slidable in a guide in the side frame and connected to a 60 lever 43 pivotally connected at 44 to the side frame. It is normally held in the upward position *i. e.* with the moistening pad clear of the envelop by a spring 45, and is operated to pull the pad down in contact with a 65 passing envelop by a projection 46 from the

shaft of the roller 21 which projection engages the free end of the lever 43.

The postage stamps are furnished to the machine in strips 50 previously divided from the sheets in which they are sold which strips are fed to the knife by which the individual stamps are cut off, by rollers 51, 52 one of which rollers is directly rotated by a star wheel 53 the rays of which are engaged by and moved through the required arc of 70 rotation by a pin 54 projecting from the inner side of the gear wheel 37, which movement may if necessary be completed by a similar projection 55 which also performs another function to be described later. The 75 upper roller 52 may be rotated by frictional contact with the lower one, or by gear wheels 52* if found necessary. From these feed rollers 51 and 52 the stamp strip is projected through a slit 56 in a plate 57 80 against which plate the severing knife slides, means being provided between the feed rollers and the slit to prevent the stamp from turning up and avoiding the slit.

The knife 58 by which the individual 85 stamps are severed from the strip 50 is preferably furnished with a serrated edge and is attached to the free end of an arm 59 pivotally mounted at 60 to the side frame of the machine. To the end of the knife lever 90 59 is secured an open rectangular casing 63 within which loosely fits a presser block 64 provided with grooves or perforations on its under side to prevent the detached stamp adhering by suction to the presser block 100 when the same is lifted. The knife blade 58 is held clear of the stamp delivery slit 56 and is drawn closely against the slit plate 57 by a spring 61 and the knife is drawn down to effect the cutting of a stamp, 105 when projected through the slit, by a rod 62 vertically slidable in the side frame 2 and connected to the end of a lever 65 pivotally mounted at 66, the downward movement of this lever being effected by a pin 55 projecting from the inner side of the gear wheel 37 and previously referred to as also serving to effect the rotation of the star wheel 53 by which the stamp feed rolls are 110 rotated.

The stamp strip may be carried for delivery to the feed rolls in any convenient manner. It is shown in the drawing as coiled around a reel 70, the under side of which bears on the upper side of a flexible band 71 120 which passes over the lower feed roll 51 and an idler 72 rotatably mounted in the end of an arm 73 provided with a spring 74 to maintain the band tight.

Having now particularly described my invention and the manner of its operation, I hereby declare that what I claim as new and desire to be protected in by Letters Patent, is:

1. As a means for sealing envelops, the 130

combination with an open bottomed envelop receptacle in which the envelops may be horizontally disposed, means for pivotally supporting the envelop holding receptacle 5 toward the back edge of the bottom, a freely rotatable roller on which the opposite edge of the receptacle rests, a plate slidable along the bottom of the receptacle past the free edge which rests upon the roller said plate 10 having a pad of absorbent material on its under side, opposed rollers between which the plate will deliver the bottom envelop removed from the receptacle, means for rotating the opposed rollers, means coöperative therewith for reciprocating the plate, and means for moistening the absorbent pad on the under side of the plate.

2. As a means for sealing envelops, the combination with a pivotally mounted envelop holding receptacle, of a freely rotatable roller supporting the edge of the envelop holding receptacle opposite to that where it is pivotally mounted, a plate slid- 20 able beneath the under side of the receptacle 25 that will engage the flap of the bottom envelop in the receptacle and deliver it be- 30 tween the roller and the edge of the receptacle resting on it said plate having a pad of absorbent material on its under side, a water containing vessel pivotally mounted 35 beneath the slidable plate and having at its free end a sponge or other absorbent material, opposed rollers between which the slidable plate will deliver an envelop re- 40 moved from the receptacle, means for rotating the rollers, means coöperative therewith for reciprocating the plate, and means for lifting the sponge holding end of the

water vessel into contact with the absorbent pad of the slidable plate during the back- 40 ward movement of the same.

3. As a means for sealing envelops, the combination with a pivotally mounted envelop holding receptacle, of a freely rotatable roller supporting the edge of the 45 receptacle opposite to that supported on the pivots, a plate slidable along the bottom of the receptacle which plate will engage the depending flap of the bottom envelop and remove it from the receptacle said plate hav- 50 ing a pad of absorbent material on its under side, a water vessel pivotally mounted beneath the plate said vessel having a place for the reception of a sponge or other absorbent material toward its free end, two 55 pair of opposed rollers the line of contact of which is in the plane of movement of the slidable plate each pair of said opposed rollers being movable apart against the resistance of springs, a supporting plate be- 60 tween the lower rollers, means for rotating the rollers, means coöperative therewith for reciprocating the slidable plate, and means for lifting the free end of the water vessel to bring the sponge into contact with the pad 65 of absorbent material on the slidable plate during the backward movement of that plate.

In testimony whereof I have signed my name to this specification in the presence 70 of two subscribing witnesses.

EDWARD J. ABBOTT.
